* cited by examiner

Primary Examiner — Dana L Meyrow(74) Attorney, Agent, or Firm — Gerald R Prettyman(57) CLAIM

The ornamental design for a bottle, as shown and described.

DESCRIPTION

FIG. 1 is a front elevation view of a bottle showing my new design, the rear elevation view being identical;

FIG. 2 is a top plan view thereof;

FIG. 3 is a bottom plan view thereof; and,

FIG. 4 is a sliced section view taken along the line 4-4 of FIG. 2.

Broken lines are included to show unclaimed subject matter only and form no part of the claimed design.

The claimed bottle is used for storing cleaning fluids and cleaning small parts within.
